UNITED STATES PATENT OFFICE

2,053,477

KNITTING MACHINE

Henry Harold Holmes, Leicester, England, assignor to Wildt and Company Limited, Leicester, England, a British company

Application April 20, 1934, Serial No. 721,587
In Great Britain April 21, 1933

8 Claims. (Cl. 66—135)

This invention consists in improvements in or relating to knitting machines and has for its object to provide an improved mechanism whereby warp-threads can be knitted in combination with a ground-thread or threads to render the resultant fabric ladderproof or substantially ladderproof within the meaning of that term as defined in the specifications of prior United States applications Nos. 415,659, 416,458, 600,780 and British Letters Patent No. 376,736.

In prior United States applications Nos. 415,659 and 416,458, fabric has been described in which the portion formed from the ground-thread served as a basis upon which the warp-threads 15 were plated to appear on the front of the fabric. While a fabric of this nature is ladderproof within the meaning of the term as defined, it suffers from the disadvantage that the appearance of the face of the fabric is to some extent marred 20 by the presence of the warp-threads. This drawback is obviated when the fabric is knitted in accordance with the description given in prior United States application No. 600,780 and British Patent No. 376,736 by which the warp-threads 25 are plated in rear of the ground-thread. A fabric of this kind is of special advantage for hose and half-hose because the outer surface exposed to view differs only very slightly and is almost indistinguishable from a plain knit fabric produced from ground-thread only.

Means for improving the rear-plating of the warp-threads or for ensuring a good quality of rear-plating have been described in the specifications of prior United States applications Nos. 642,254 and 642,246 by which each warp-thread is released prior to the loop-drawing operation of the needle taking the thread, and the present invention, although it is not limited to employment in conjunction with such thread-releasing 40 means may be employed in addition thereto with benefit to the resultant fabric. The invention is applicable to any mechanism whereby a ladder-proof fabric is produced from combined ground- and warp-threads and in which means is provided whereby, prior to loop formation on each needle a length of wale-thread required for each loop is drawn off independently of the needle movement as, for instance, by the members 34, 35 and 36 of prior British Patent No. 364,039 or 45 cam 37 of prior United States application No. 642,254. Such means will be referred to herein-after as "a draw-off device".

According to the present invention the thread-drawing device is so formed, or is combined with other means which will operate in an equivalent

manner, as to impart a tension to each warp-thread substantially at the moment of completion of the loop-drawing movement of the needle. The purpose of this additional tensioning is to apply a slight pull immediately prior to knocking over the loops, to all the warp-threads in succession sufficient to even up any slight tendency that the action of the thread-drawing device may have to provide a surplus of the individual warp-threads over and above that required for the 10 individual loops.

For instance, it is possible to form the loop-drawing device with a cam-rise which will impart the required slight additional pull substantially at the moment of completion of the loop-drawing 15 movement of the needle.

This improvement is of particular advantage in rear-plated-warp-thread fabric because if, during formation of any loop, a surplus of warp-thread is available beyond that required for the 20 loop formation the tendency is for the warp-thread to ooze through the fabric to show somewhat on the face or right side thereof. Such oozing spoils the appearance of the fabric and this is obviated in the present invention by elimination of the surplus warp-thread at the moment 25 of loop formation.

In order that the invention may be more clearly understood a preferred construction of apparatus embodying the invention will now be 30 described with the aid of the accompanying drawings, in which—

Figure 1 is an elevation partly in section of those parts of a knitting machine and warp-thread feeder mechanism sufficient to show the 35 essential features of the invention.

Figure 1a is a view looking from the right of Figure 1 to show only the stitch-cam and one of the needles in their relative positions at the moment of engagement of a warp-thread by the 40 additional tensioning device according to the invention, and

Figure 2 is a plan on the line 2—2 of Figure 1.

Like reference numerals indicate like parts in the several figures of the drawings.

In the portion of the mechanism illustrated the needle-cylinder is shown at 10 with one needle 11 in position. It will be understood that the cylinder will be completely filled with needles in the ordinary way. The cam-box is indicated 50 at 12, the sinker-cam ring at 13 and sinkers at 14.

Coaxial with the needle-cylinder and immediately above it is the feeder-head similar in its main essential to that described in detail in the specification of prior British Letters Patent No. 55

364,039 to which reference is now directed for a more complete understanding of this part of the machine. Warp-thread feeders 15 are shown as projecting from the feeder-head indicated generally by reference numeral 16. The feeder 15 on the left-hand side is shown in its retracted position whereas that on the right-hand side is shown as having been reprojected as described for instance in copending United States application No. 722,272 to hold its warp-thread forwardly in the needle during the last portion of the descent of the needle down the stitch-cam.

As described in the last-mentioned specification the cam serving normally to move the thread-guides outwardly at the commencement of their wrapping operation is indicated at 17 and the reprojecting cam is shown at 18. Cam 19 acts as described in British patent specification No. 364,039 to deflect the thread-guides subsequently to their projection by the cam 17 in order to bring about the wrapping movement of the thread-guides.

A cam-ring 20 is now provided to act as a draw-off member for the warp-threads and is formed with a gradual rise 21 which draws off in succession from each warp-thread supply an amount of warp-thread sufficient for the wrapping operation and releases the drawn off thread to the needles as the thread-guide is deflected laterally by cam 19 and returned inwardly by a return cam (not illustrated) associated with cam 17. A second cam-rise reaches its highest point at 22 and serves as a second thread draw-off cam to draw off amounts of warp-thread required for loop formation as the needle descends the stitch-cam.

In accordance with the present invention an additional cam 23, circumferentially adjustable on the cam-ring 20 by means of screws 24 and a slot 25 in the cam-ring, is provided to press on the warp-threads to apply the requisite tension immediately prior to the knocking over point in the loop-drawing operation. The relative positions of cam 23, feeder 15, needle 11, and stitch-cam 26 are clearly indicated in Figures 1 and 1a in which Figure 1a shows the relative positions of the stitch-cam and needle substantially at the time of knocking over, and Figure 1 (taken in conjunction with Figure 2) shows at the same moment the relative positions of the needle, thread-guide and cam 23.

It will be observed that the cam-rises 21 and 22 take the place of the draw-off members 34 and 36 respectively illustrated in prior British Patent No. 364,039. Also the cam-rise 22 may be considered as the equivalent of the cam 37 in United States patent application No. 642,254.

The wrap-threads, indicated in the drawings by the reference numeral 115 will, in their passage from the wrap-thread supply bobbins to the wrap-thread feeders 15 be subjected to any desired and known form of tensioning as this follows the usual practice in knitting machines employing wrap-threads. It will be understood, therefore, that the cam rises 21 and 22 will draw-off the required amounts of wrap-threads on each operation and will yield those threads under the normal tension to the needles during wrapping and loop-forming operations. As the tensioning means which are operable on the wrap-threads in their passage to the feeders 15 are well known and their action well understood, and, moreover, as of themselves they constitute no part of the present invention, illustration of them is unnecessary.

In Figure 1 a ground-thread 116 is illustrated as guided by a thread-guide 117 to the needles and it will be understood that the wrap-threads are supplied to the needles in addition to the ground-thread which forms what may be considered the basic fabric.

The invention is not to be limited by the particular construction and arrangement of cam 23 as it may be applied to the mechanism in any other preferred manner to operate in a similar way.

Briefly the operation of the mechanism described is as follows:—

After each individual needle has been raised its associated thread-feeder is first moved outwardly by cam 17 on one side of the needles and at the same time the cam 21 draws off from the warp-thread supply of that feeder a length of thread sufficient for the purpose of wrapping round the needle. The feeder is then deflected by cam 19 and is retracted past the other side of the needle by the return cam co-operating with cam 17, thus completing the wrapping movement. During the completion of the wrapping the yarn is yielded to the needle down the rear slope of cam 21, the relative direction of movement of that cam with respect to the warp-threads being indicated by the arrow in Figure 2. The cam-ring 20 continues to rotate in the same direction and at a later stage in the operation each of the warp-threads is engaged by the cam 22 to draw off a further supply of thread sufficient for loop formation. After this has been completed the stitch-cam commences to act upon the needle and as it nears the lowest point of the stitch-cam, cam 18 reprojects the feeder into the position illustrated on the right-hand side of Figure 1 so as to hold the warp-thread forwardly into the hook of the needle in order to assist in accurately plating the warp-threads in rear of the ground-thread in the finished fabric. Just as each needle reaches the lowest part of the stitch-cam 26, cam 23 engages its warp-thread to apply the requisite slight tension in accordance with the present invention.

I claim:

1. In a knitting machine the combination of a bed of needles, feeding means to supply ground and wrap threads to the needles, needle actuating means, a wrap thread draw-off device for drawing lengths of thread required for loop formation and to yield those threads to the needles under tension, and means to impart to the wrap threads, substantially at the moment of completion of the loop-drawing movements of the needles taking those threads a momentary tension in order to apply an increased pull on the wrap threads to assist in positioning them in their respective needle heads relatively to the ground thread.

2. In a knitting machine the combination of a bed of needles, feeding means to supply ground and wrap threads to the needles, needle actuating means, wrap thread draw-off means to draw from each wrap thread supply for each loop forming operation of the needles substantially the lengths of thread required for loop formation and to yield those lengths to the needles under substantially constant tension, and means operating on each wrap thread to apply a momentary tension thereto to effect an increased pull on the wrap threads substantially at the moment of completion of the loop-drawing operations.

3. In a knitting machine the combination of a bed of needles, feeding means to supply ground

and wrap threads to the needles, needle actuating means, and a wrapping thread draw-off device comprising a cam plate having at least two cam rises one of which engages the threads to draw off from each wrap thread supply an amount of thread required for loop formation and another of which serves to apply a momentary tension to the wrap threads to effect an increased tension thereon substantially at the moment of completion of the loop-drawing movements of the needles.

4. In a knitting machine the combination according to claim 3 in which the cam plate has three cam rises two of which function as already claimed and the third of which serves to draw off from each wrap-thread supply an amount of yarn required for wrapping the needles prior to supplying the needles with thread for loop formation.

20 5. In a knitting machine the combination of a bed of needles, feeding means to supply ground and wrap threads to the needles, needle actuating means, and a wrap thread draw-off device comprising a cam plate coaxial with the needle bed and having on it at least two cam rises one of which engages the threads to draw off from each wrap thread supply an amount of thread required for loop formation, and another of which serves to apply a momentary tension to the wrap threads 30 to effect an increased pull thereon substantially at the moment of completion of the loop-drawing movements of the needles.

6. In a knitting machine the combination according to claim 5 in which the cam plate has

three cam rises two of which function as already claimed and the third of which serves to draw off from each wrap-thread supply an amount of yarn required for wrapping the needles prior to supplying the needles with thread for loop formation. 5

7. In a knitting machine the combination of a bed of needles, feeding means to supply ground and wrap threads to the needles, needle actuating means, draw-off means operable on the wrap threads to draw off and supply to the needles for each needle operation the required amount of yarn under normal tension, and additional means operable on the wrap threads substantially at the moment of completion of the loop-drawing movements of the needles taking those threads to apply a momentarily increased tension to the threads.

8. In a knitting machine the combination of a bed of needles, feeding means to supply ground and wrap threads to the needles, needle actuating means, means to draw off and supply to the needles under normal tension the amount of wrap thread required for the needle wrapping movement, means operating thereafter to draw off and supply to the needles the amount of wrap thread required for loop formation, and additional means operable on the wrap threads to apply a momentarily increased tension substantially at the moment of completion of the loop-drawing movements of the needles taking those threads. 25 30

HENRY HAROLD HOLMES.
